DESIGN FOR A COMBINED MANICURE BOWL AND BRUSH

Margaret McKeen, Los Angeles, Calif.

Application July 30, 1938, Serial No. 78,984

Term of patent 3½ years

To all whom it may concern:

Be it known that I, Margaret McKeen, a citizen of the United States and a resident of Los Angeles, in the county of Los Angeles, State of California, have invented a new, original, and ornamental Design for a Combined Manicure Bowl and Brush, of which the following is a specification, reference being had to the accompanying drawing, forming part thereof.

In the drawing:

Fig. 1 is a plan view of a combined manicure bowl and brush, showing my new design.

Fig. 2 is a sectional view taken substantially on line 2—2 of Fig. 1, in the direction of the arrows.

I claim:

The ornamental design for a combined manicure bowl and brush, as shown and described.

MARGARET McKEEN.
